HIGH FREQUENCY GASEOUS CONDUCTION
LAMP

Stewart C. Whitman, Jackson Heights, N. Y.

Application April 18, 1932, Serial No. 605,990

25 Claims. (Cl. 176—122)

This invention relates to new and useful improvements in the art of recording sound on film and more particularly to a gaseous conduction lamp operated by radio frequency energy to accomplish the desired result, this application being a continuation in part of my copending application, Serial Number 507,220, filed January 27, 1931.

An object of the invention resides in the production of a lamp wherein the respective glows from a pair of electrodes occupy the same space.

A further object of the invention is to produce a lamp of high actinic value.

A still further object is to provide a lamp whose light source is of optimum size, shape, and brilliancy for the necessary optical reduction.

Still another object of the invention is to provide a lamp of rugged construction and one capable of long life.

With these and numerous other objects in view, my invention consists in the novel features of construction, combination and arrangement of parts as will be hereinafter referred to and more particularly pointed out in the specification and claims.

In the accompanying drawings forming a part of this application:

Figure 1 is a side elevation, with parts broken away and parts in section, showing a lamp constructed in accordance with my invention;

Figure 2 is a horizontal section as seen on the line 2—2 of Figure 3;

Figure 3 is a vertical section as seen on the line 3—3 of Figure 2;

Figure 4 is an elevation with parts broken away and parts in section illustrating a modification of my invention;

Figure 5 is a similar view thereof taken on a plane at right angles to the plane of Figure 4;

Figure 6 is an enlarged fragmentary vertical section as seen on the line 6—6 of Figure 5;

Figure 7 is a similar view as taken on the line 7—7 of Figure 6; and

Figure 8 is a horizontal section as seen on the line 8—8 of Figure 6.

In the recording of sound on film, the photographic record is usually in the form of narrow discrete parallel lines on the edge of the film. The width and the density of these lines are responsible for the frequencies and volumes of the recorded sounds. For this reason, it is desirable that the modulated light source producing this photographic record be rectangular in shape.

It is also desirable that the variation in sound

intensity to be photographed be faithfully followed by the intensity of light emitted from the lamp. It is my purpose to describe here a lamp which best fulfills these requirements.

Figure 1 shows a side elevation of a preferred form. Figure 2 shows a horizontal cross section and Figure 3 a vertical cross section. Inasmuch as alternating current is to be used in connection with this lamp, the two electrodes must be of equal area since they act alternately as cathodes. The area of these electrodes must be carefully determined so that the required light intensity may be obtained without prohibitive disintegration. It is desirable to confine the glow discharge between the two inner surfaces of these electrodes in order to obtain a clearly defined rectangular source of light. For this reason, the outer surfaces of the electrodes are shielded with an insulating material. The lead wires and support wires running to these electrodes are also shielded in order to confine the glow between the rectangular electrodes. The distance at which the electrodes are spaced from each other is a function of current density, gas pressure and electrode material. Taking these factors into consideration, the spacing is adjusted so that the cathode glows surrounding each electrode apparently overlap and the apparent width of the arc between the electrodes is constant. Thus, during operation the light source appears as a brilliant thread of light between the electrodes with a narrow dark space adjacent to the surface of each. As the impressed voltage increases, the dark space surrounding each electrode shrinks slightly and the width of the luminous portion of the arc increases. This is undesirable since the linearity of intensity is impaired. Therefore, the electrodes are mounted to converge slightly toward the top, that is, nearest the film. Thus, when the luminous discharge becomes wider or occupies a greater part of the area between the electrodes, the mean center of light is brought closer to the film. In this manner, the variation in the width of the arc is compensated for. Under proper conditions, the luminous portion of the arc and the dark spaces can be made to appear stationary, unchanging in dimensions, and varying only in intensity under the influence of a modulated signal voltage.

The components are assembled so that the area of the glow does not change with the change in signal intensity. This results in a change in light intensity only. The electrode material must be chosen so that the glow does not become "spotty", since this would cause a change in the

"mean intensity distance" with respect to the film. The electrodes must be small enough to result in recording light intensities on available power and the proper material selected to prevent undue sputtering. Since mercury constitutes part of the gas filling contained in the lamp, the vapor pressure of the mercury at the operating temperature must be considered in reference to the dark spaces and arc widths discussed above. 5 This is accomplished by choosing the proper length of glass envelope for the proper heat radiation. As is well known, the mercury vapor pressure in a lamp of this type is determined by the coolest part of the envelope. 10 Using a lamp constructed according to the present invention, a very simple optical system may be constructed to be used therewith. Since this is the case, the optical system may be constructed economically of quartz. Hence, the lamp envelope may be economically constructed of 15 "Uviolet", "Ultrasol", or "Corex" glass, and advantage taken of the actinic ultra-violet radiation. Inasmuch as a large percentage of the light radiated is a result of the mercury discharge and inasmuch as the mercury vapor pressure is 20 very low, ultra-violet radiation of short wave length is emitted. In fact, the most prominent radiation is of wave length 2537 A. U. as a result of the P_2 — D_3 energy level transition. This light 25 is extremely active actinically and constitutes one reason why the mercury vapor pressure is kept low.

Having explained these interdependent relations, I will now describe a commercial adaptation 30 which has been found to work very satisfactorily.

In describing the invention, I shall refer to the drawings in which similar reference characters designate corresponding parts throughout the several views. Referring to Figure 1, the tubular glass envelope 6 of "Corex" glass of approximately 35 eight inches by one inch is utilized. This envelope is substantially flat on the top. The two rectangular electrodes 11 of dimensions one centimeter by two centimeters, are mounted on the glass stem 7. The electrodes are mounted 40 on the shielded support wires 12 and the lead wires 8 and 9 sealed thereto. I have discovered that electrodes made of a chromium iron alloy or preferably of beryllium are most advantageous 45 for my purpose to reduce electrode disintegration to a minimum. The spacing between the electrodes is 1.2 millimeters at the bottom and 1 millimeter at the top. The electrodes are shielded with mica sheets 13 on the outer surface secured thereto by clips 14 and the glow thereby 50 insulated from these portions. The electrodes may be mounted very close to the flattened top portion of the envelope, in order to bring the light source as close as possible to the film. By 55 this construction, a rugged mount results which is free from vibration effects. I have found that any such vibration results in small changes in arc width which further results in a superimposed frequency modulation in the recorded sound. The lamp thus constructed is exhausted 60 in the usual manner, care being taken to de-gasify the metal parts.

In this particular adaptation of the invention, I have found a mixture of mercury vapor and 65 argon as most satisfactory. A small drop of pure mercury is distilled into the lamp and spectroscopically pure argon admitted to a pressure of 12 millimeters of mercury.

I have found in experimenting with my invention as hereinabove described that certain gen-

eral relations exist among the various factors entering into the construction of the lamp. The most desirable gas filling consists in a mixture of an inert gas such as argon, neon or helium at pressure of from five to 20 millimeters, and 5 mercury vapor at a pressure corresponding to temperatures of from 30° to 50° C. Using this gas filling, best results are obtained by operating the lamp at current densities of .030-.040 ampere per square centimeter of electrode area. The 10 ratio of electrode spacing in millimeters to gas pressure measured in millimeters of mercury may cover a range of 1-8 to 1-12.

I have further found that a ratio of approximately 10 to 1 between electrode height and spacing 15 dimension thereof is productive of maximum brilliancy for given input power.

In Figures 4 to 8, inclusive, I have shown a slight modification of my invention, wherein the electrodes are provided with a more effective 20 shielding means than that illustrated in the previously described adaptation of my invention. In this form of the invention so illustrated the lamp includes an envelope 15 of the same character and shape as that previously described. The 25 stem 16 therein includes the three glass tubular upstanding projections 17, 18, and 19, respectively. The projections 17 and 19 are provided with bores through which extend lead-wires 20 which connect respectively with electrodes 21. 30 These particular electrodes 21 are similar to the electrodes 11 of the previously described form. In extending the lead wires 20 through the projections 17 and 19, protection against electric discharge is afforded at these points. Enclosing 35 the electrodes 21 is an insulating member 22 composed of a refractory insulating material. This insulator is rectangular in cross section and the inner faces of its end walls are slotted as shown 40 at 23 to receive the electrodes 21 as clearly shown in Figure 8. A bottom wall 24 is formed on this insulator which rests upon the upper peripheral edges of the upstanding projections 17, 18, and 19. Formed on said bottom wall is a depending 45 tubular neck portion 25 which receives therein the projection 18 forming a rigid support for the insulator. This construction is clearly shown in Figure 6 of the drawings, wherein is also disclosed 50 openings 26 in the bottom wall 24 through which extend the lead-wires 20. The upper end portion of the insulator is open to provide a restricted aperture through which the light is emitted.

With the use of such an insulator as I have herein described and shown, it will be seen that no undesirable discharges can take place except 55 between the inner faces of the electrodes.

While I have particularly described the elements best adapted to perform the functions set forth, it is obvious that various changes in form, proportion and in the minor details of construction may be resorted to, without departing from the spirit or sacrificing any of the principles of the invention.

Having thus described the invention, what is 65 claimed is:

1. In a gaseous conduction lamp, a pair of 70 rectangular electrodes of equal areas formed of a metal surfaced with beryllium, the ratio of whose length to height is approximately two to one.

2. In a gaseous conduction lamp, a pair of substantially parallel spaced electrodes of equal size and shape having a ratio of approximately ten to one between electrode height and spacing dimension thereof.

3. In a gaseous conduction lamp, a partially evacuated envelope, a pair of substantially parallel spaced electrodes therein of equal areas and a mixture of argon and mercury vapor contained in said envelope, the pressure of said mixture measured in millimeters being in the proportion of approximately ten to one with respect to the spacing in millimeters between the electrodes. 5
4. In a gaseous conduction lamp, a partially evacuated envelope, a pair of substantially parallel spaced electrodes therein of equal areas formed of a metal surfaced with beryllium, and a mixture of argon and mercury vapor contained in said envelope, the pressure of said mixture measured in millimeters being in the proportion of approximately ten to one with respect to the spacing in millimeters between the electrodes. 10
5. In a gaseous conduction lamp, a partially evacuated envelope, a pair of substantially parallel spaced electrodes therein of equal areas, and a mixture of argon and mercury vapor contained in said envelope, the pressure of said mixture measured in millimeters being in the proportion of approximately ten to one with respect to the spacing in millimeters between the electrodes. 15
6. In a gaseous conduction lamp, a partially evacuated envelope containing a mixture of argon and mercury vapor, and a pair of spaced electrodes of equal areas tending to converge upwardly, the pressure of said gaseous mixture measured in millimeters being in the proportion of approximately ten to one with respect to the spacing in millimeters between the electrodes. 20
7. In a gaseous conduction lamp, a partially evacuated envelope containing a mixture of argon and mercury vapor, and a pair of spaced electrodes of equal areas formed of a metal surfaced with beryllium, tending to converge upwardly, the pressure of said gaseous mixture measured in millimeters being in the proportion of approximately ten to one with respect to the spacing in millimeters between the electrodes. 25
8. In a gaseous conduction lamp, a partially evacuated envelope containing a mixture of argon and mercury vapor, and a pair of spaced electrodes of equal areas formed of a metal surfaced with beryllium, said electrodes being mounted to converge together toward one end of said envelope. 30
9. In a gaseous conduction lamp unit, a partially evacuated envelope containing a mixture of inert gas with mercury vapor, and a pair of spaced electrodes mounted therein, said electrodes being of such areas and in such relative positions that their respective cathode glow discharges can be made to occupy the same positions in the space between said electrodes by regulating the current value, and means for limiting the current value to cause said glow discharges to be spacially coincident. 35
10. In a gaseous conduction lamp, a partially evacuated envelope, a pair of substantially parallel spaced electrodes therein of equal areas and a mixture of argon and mercury vapor contained in said envelope, the pressure of said mixture measured in millimeters being in the proportion of approximately ten to one with respect to the spacing in millimeters between the electrodes, and an insulating member housing said electrodes and provided with a restricted light passage at one end thereof. 40
11. In a glow lamp unit for sound on film recording purposes, a glass envelope, a gas filling, two glow discharge electrodes of equal areas, said electrodes being of such areas and in such relative positions that their respective cathode glow discharges can be made to occupy the same positions in the space between said electrodes by regulating the current value, and means for limiting the current value to cause said glow discharges to be spacially coincident. 45
12. In a gaseous conduction lamp, a partially evacuated envelope, a pair of substantially parallel spaced electrodes therein of equal areas, and a noble gas contained in said envelope having a pressure measured in millimeters being in the proportion of approximately ten to one with respect to the spacing in millimeters between the electrodes. 50
13. In a gaseous conduction lamp, a partially evacuated envelope, a pair of substantially parallel spaced electrodes therein of equal areas, and a mixture of a noble gas and mercury vapor contained in said envelope, the pressure of said mixture measured in millimeters being in the proportion of approximately ten to one with respect to the spacing in millimeters between the electrodes. 55
14. In an electrical optical reproducing system, a gaseous conduction lamp comprising an envelope and a pair of electrodes of substantially equal areas positioned adjacent each other but in spaced relation, and mounted in said envelope, said envelope being filled with a noble gas of determined pressure, and a source for applying to said electrodes an alternating potential of such value that the discharge between said electrodes corresponds to a current density of substantially 0.03 to 0.04 ampere per square centimeter of electrode area. 60
15. In a gaseous conduction lamp unit, a gaseous conduction lamp comprising an envelope and a pair of electrodes of substantially equal areas positioned adjacent each other but in spaced relation and mounted in said envelope, said electrodes being mounted to mutually diverge toward the end from which they are mounted, said envelope being filled with an inert gas of determined pressure, and a source for applying to said electrodes an alternating potential of such value that the discharge between said electrodes corresponds to a current density of substantially 0.03 to 0.04 ampere per square centimeter of electrode area. 65
16. In a gaseous conduction lamp unit, a gaseous conduction lamp comprising an envelope and a pair of electrodes of substantially equal areas positioned adjacent each other but in fixed spaced relation and mounted in said envelope, said envelope being filled with an inert gas of determined pressure, and a source for applying to said electrodes an alternating potential of such value that the luminous discharges between said electrodes corresponding to successive opposite halves of a cycle overlap over substantially their entire areas, whereby a line source of light of substantially unchanging area is produced without apparent flicker. 70
17. In a gaseous conduction lamp unit, a gaseous conduction lamp comprising an envelope and a pair of electrodes of substantially equal areas positioned adjacent each other but in fixed spaced relation and mounted in said envelope, said electrodes being mounted to diverge toward the end from which they are mounted, said envelope being filled with an inert gas of determined pressure, and a source for applying to said electrodes an alternating potential of such value that the luminous discharges between said electrodes corresponding to successive opposite 75

- halves of a cycle overlap over substantially their entire areas, whereby a line source of light of substantially unchanging area is produced without apparent flicker.
- 5 18. In the operation of a gaseous conduction lamp having a pair of fixed electrodes of equal area and a filling of inert gas, the method of obtaining a line source of light which consists in applying to said electrodes an alternating potential of such value that the luminous glows between said electrodes corresponding to successive opposite halves of a cycle overlap over substantially their entire area.
- 10 19. In a gaseous conduction lamp to operate at a determined alternating potential, an envelope, a pair of electrodes of substantially equal areas positioned adjacent each other but in fixed spaced relation and mounted in said envelope, said envelope being filled with a noble gas at a pressure such that the ratio of gas pressure measured in millimeters of mercury to electrode spacing in millimeters is approximately ten to one, said electrodes having such area that at said pressure and said determined alternating potential the discharge current density is approximately 0.03 ampere per square centimeter of electrode area.
- 15 20. In a gaseous conduction lamp to operate at a determined alternating potential, an envelope, a pair of electrodes of substantially equal areas positioned adjacent each other but in fixed spaced relation and mounted in said envelope, said electrodes being mounted to mutually diverge toward the end from which they are mounted, said envelope being filled with a noble gas at a pressure such that the ratio of gas pressure measured in millimeters of mercury to electrode spacing in millimeters is approximately ten to one, said electrodes having such area that at said pressure and said determined alternating potential the discharge current density is approximately 0.03 ampere per square centimeter of electrode area.
- 25 21. In a recording lamp, an envelope having one flattened end adapted to be positioned adjacent a record film, a pair of adjacent but spaced electrodes of equal areas mounted adjacent the flattened end of said envelope to mutually converge together toward said flattened end, and a noble gas in said envelope, the pressure of said gas measured in millimeters being in the proportion of approximately ten to one with re-
- spect to the mean spacing in millimeters between said electrodes.
22. In a gaseous conduction lamp, an envelope having a flattened end, a pair of spaced electrodes of substantially equal areas mounted in said envelope adjacent said flattened end to mutually converge toward said flattened end with such slope that their spacing apart is about 0.2 millimeter less at the ends of said electrodes near said flattened end of said envelope than at the other ends of said electrodes, and a noble gas in said envelope, the pressure of said gas measured in millimeters being in the proportion of approximately ten to one with respect to the mean spacing in millimeters between said electrodes.
- 10 23. In a gaseous conduction lamp, an envelope, an insulating member provided with a central rectangular aperture open at one face of said insulating member but closed at the opposite face, a pair of electrodes insulated from each other, means for maintaining said electrodes respectively in position against the long sides of said rectangular aperture in spaced relation to each other, and means for mounting said insulating member in said envelope.
- 15 24. In a gaseous conduction lamp, an envelope, an insulating member provided with a central rectangular aperture open at one face of said insulating member but closed at the opposite face, a pair of electrodes insulated from each other, said insulating member being provided with terminal slots at each end of the long faces of said rectangular recess, said slots being adapted to respectively receive said electrodes and hold them tightly against the long faces of said aperture, and means for mounting said insulating member in said envelope.
- 20 25. In a gaseous conduction lamp, an envelope, an insulating member provided with a central rectangular aperture open at one face of said insulating member but closed at the opposite face, a pair of electrodes insulated from each other, means for maintaining said electrodes respectively in position against the long sides of said rectangular aperture in spaced relation to each other, and means for mounting said insulating member in said envelope, said electrodes being so mounted that they converge toward the open end of said aperture.
